(57) **CLAIM**

The ornamental design for an air intake device for an internal combustion engine, as shown and described.

DESCRIPTION

FIG. 1 is a perspective view showing an air intake device for an internal combustion engine according to our new design; FIG. 2 is a left side elevational view thereof; FIG. 3 is a right side elevational view thereof, opposite the first side elevational view of FIG. 2; FIG. 4 is a front end elevational view thereof; FIG. 5 is a rear end elevational view thereof, opposite the first end elevational view of FIG. 4; FIG. 6 is a top plan view thereof; and, FIG. 7 is a bottom plan view thereof, opposite the first plan view of FIG. 6.

The dashed broken lines illustrate portions of the air intake device for an internal combustion engine that form no part of the claimed design. The dot-dash broken lines depict boundary lines and form no part of the claimed design.
